UNITED STATES PATENT OFFICE.

JAMES H. DIAMOND, OF PITTSBURG, PENNSYLVANIA, ASSIGNOR TO MARY B. McCLELLAND, OF ALLEGHENY, PENNSYLVANIA.

DESIGN FOR A GAS-STOVE.

SPECIFICATION forming part of Design No. 31,415, dated August 15, 1899.

Application filed July 10, 1899. Serial No. 723,428. Term of patent 7 years.

To all whom it may concern:

Be it known that I, JAMES H. DIAMOND, a citizen of the United States, residing at Pittsburgh, in the county of Allegheny, State of Pennsylvania, have invented and produced a new and original Design for a Gas-Stove, of which the following is a specification, reference being had to the accompanying drawings, forming part thereof.

- o Figure 1 indicates a perspective view of a gas-stove made in accordance with my design. Fig. 2 is a transverse section on line $x-x$ of Fig. 1.

My design consists of a vertical frame A, in which is located a vertical plate B, concave in configuration and covered with asbestos, giving it a rough or fluffy appearance, as shown

in Fig. 2, at the base of which is located in said frame the semicircular burner C, which conforms in curvature with said base-plate 20 and platform or reflector D, the inner edge of which adjacent to the burner conforms in curvature therewith.

What I claim is—

The design for a gas-stove substantially as 25 herein shown and described.

In testimony whereof I have hereunto affixed my signature in the presence of two subscribing witnesses.

JAMES H. DIAMOND. [L. S.]

Witnesses:

M. G. O'NEIL,
CLARENCE A. WILLIAMS.
